VALVE CONTROL MEANS

Otto Thiel, Detroit, Mich.

Application April 27, 1944, Serial No. 533,030

3 Claims. (Cl. 137—69)

This application relates to vent valve control means for gas charged liquid devices, such as carbonators.

The control means herein disclosed may be understood upon reference to the appended drawings, whose,

Figure 1 shows the device with the valve closed, and whose,

Figure 2 is a section on line 2—2 of Figure 1.

The drawing shows a sealed bottom tank 10 whose upper end is closed by a head 11 having a valved vent opening adapted to be closed by a needle valve 13 pivotally connected at its lower end 14 to a counterweight lever 15 pivotally mounted at 16 on a boss 17 of the head 11, the pivot 16 also mounting a cross lever 18 which has an end 19 connected to a link 20 to which is fixed a cup 21, the lower end of the link 20 being pivotally connected at 22 to a cross lever 23 mounted on a fixed pivot 24 formed on a stop 25 fixed to the side of the tank 10; the other end 26 of the cross lever 23 is pivotally connected to the lower end of a counterweight rod 27 whose upper end 28 is pivotally connected to the cross lever 18. A parallelogram for parallel motion is formed by the cross levers 18 and 23, the link 20, and the counterweight rod 27, so that parts 20 and 27 are guided to move truly vertically in the tank in response to movement of the cross levers.

When rod 27 moves up, it strikes lever 15 to open the valve, and when rod 27 moves down, it frees lever 15 to close the valve.

An inverted cup 30 is fixed to the upper end of the link 20.

Integral with bracket 25 is a bracket 40 which pivotally mounts at 41, a latch in the form of a bellcrank 42 having a crosspin 43 which cooperates with the upper and lower cams 44 and 45 of a plate 46 fixed to the lower end of link 20 to provide a latch for this link. The bellcrank 42 constantly tends to rock counter-clockwise on its pivot 41 and functions to delay the movement of link 20 by engaging either of the cams 44, 45 of plate 46 on link 20.

The operation is as follows:

Assume the cycle starts with the valve open and the water level low, well below the upper end of the lower cup 31 which is filled with water and whose weight has overcome the counterweight 27 and has lowered valve 13 to open. The upper cup 30 is empty and has no effect. Pin 43 engages cam 45 to latch the linkage in the valve open position. Not until cup 30 rises to overcome the weight of bellcrank 42 can the parts move. The weight of cup 21 maintains valve 13 open.

If water is admitted to a level above cup 21, that cup will lose the greater portion of its effective weight, being completely submerged, and will no longer oppose the counterweight. However, nothing will happen until the water level becomes high enough to raise the upper cup 30 to overcome the weight of bellcrank 42 and release the latch at 43—45, whereupon the counterweight 27 drops quickly to permit lever 15 to close the valve 13, to the position of Figure 1, with a snap action.

If enough water be drawn off so that the water level drops below the upper edge of cup 21, sufficient to give that cup weight well in excess of counterweight 27 and the retaining force produced by the latch acting at 43—44, then the valve will be opened with a snap action because cup 21 will drop, after a time delay, since by this time it has sufficient weight, whereupon the linkage will move and the valve will open fully.

Not until lower cup 21 has attained a considerable weight will it release the latch at 43—44 to open the valve, and not until the buoyant force on cup 30 is considerable in amount, will the latch at 43—45 be released to permit the valve to close.

Now having described the control means herein disclosed, reference should be had to the claims which follow.

I claim:

- 30 1. A control means for the upper head vent valve of a tank having a gas charged liquid inlet and a gas charged liquid outlet, and having a vent, and a valve below it for rising and closing it or for dropping and opening it, comprising a counterweighted linkage connected to the valve and having a normal tendency to move in a manner to bias said valve upwardly to close, but also movable in a manner to bias said valve downwardly to open, a latch means for the linkage normally inhibiting it from moving, an open top liquid filled cup at the lower end of the tank operatively connected to the latch means and linkage in such a manner that when the liquid level drops below the upper end of said lower cup, it drops and overcomes the latch means to release it and overcomes the effect of the counterweight on the linkage to move the linkage and lower the valve to open, but when the liquid level is above the said lower cup, it exerts no bias on the latch means or linkage, an open bottom cup 50 at the upper end of the tank arranged to move up or down with the rise or fall of the liquid level and operatively connected to the linkage and latch means in such a manner that when the said upper cup is raised it overcomes the latch means, and 55 moves the linkage to close the valve, the latch

means operating to hold the linkage in valve closed position, if it is there, or in valve open position, if it is there, said latch means comprising a latch member and two cams connected to the cups for providing snap release of the latch member, in either of two directions of movement of the cams, whereby, when the weight of the lower cup is in excess of the counterweight, but only then, the lower cup will drop, to actuate one cam to release the latch member and will move the linkage to move the valve to open with a snap action, the latch member then moving to relatch the linkage, but this time in its valve-open position, and whereby, when the upper cup is raised by a rise of the liquid level, it will move the other cam to release the latch member and the linkage will move to valve closing position with a snap action, the latch member then moving to relatch the linkage, but this time in its valve-closed position.

2. A control means for the upper head vent valve of a tank having a gas charged liquid inlet and a gas charged liquid outlet, and having a vent, and a valve below it for rising and closing it or for dropping and opening it, comprising a counterweighted linkage connected to the valve and having a normal tendency to move in a manner to bias said valve upwardly to close, but also movable in a manner to bias said valve downwardly to open, a latch means for the linkage normally inhibiting it from moving, an open top liquid filled cup at the lower end of the tank operatively connected to the latch means and linkage in such a manner that when the liquid level drops below the upper end of said lower cup, it drops and overcomes the latch means to release it and overcomes the effect of the counterweight on the linkage to move the linkage and lower the valve to open, but when the liquid level is above the said lower cup, it exerts no bias on the latch means or linkage, an open bottom cup at the upper end of the tank arranged to move up or down with the rise or fall of the liquid level and operatively connected to the linkage and latch means in such a manner that when the said upper cup is raised it overcomes the latch means, and moves the linkage to close the valve, the latch means operating to hold the linkage in valve closed position, if it is there, or in valve open position, if it is there, said latch means comprising a latch member and two cams connected to the cups for providing snap release of the latch member, in either of two directions of movement of the cams, whereby, when the weight of the lower cup is in excess of the counterweight, but only then, the lower cup will drop, to actuate one cam to release the latch member, and will move the linkage to move the valve to open with a snap action, the latch member then moving to relatch the linkage, but this time in its valve-open position, and whereby, when the upper cup is raised by a rise of the liquid level, it will move the other cam to release the latch member and the linkage will move to valve closing position with a snap

action, the latch member then moving to relatch the linkage, but this time in its valve-closed position, the linkage comprising a parallelogram having two vertical members, one of which is counterweighted to give the linkage a tendency to move to valve closing position, and the other one of which fixedly mounts the upper inverted cup and the lower cup.

3. A control means for the upper head vent valve of a tank having a gas charged liquid inlet and a gas charged liquid outlet, and having a vent, and a valve below it for rising and closing it or for dropping and opening it, comprising a counterweighted linkage connected to the valve and having a normal tendency to move in a manner to bias said valve upwardly to close, but also movable in a manner to bias said valve downwardly to open, a latch means for the linkage normally inhibiting it from moving, an open top liquid filled cup at the lower end of the tank operatively connected to the latch means and linkage in such a manner that when the liquid level drops below the upper end of said lower cup, it drops and overcomes the latch means to release it and overcomes the effect of the counterweight on the linkage to move the linkage and lower the valve to open, but when the liquid level is above the said lower cup, it exerts no bias on the latch means or linkage, an open bottom cup at the upper end of the tank arranged to move up or down with the rise or fall of the liquid level and operatively connected to the linkage and latch means in such a manner that when the said upper cup is raised it overcomes the latch means, and moves the linkage to close the valve, the latch means operating to hold the linkage in valve closed position, if it is there, or in valve open position, if it is there, said latch means comprising a latch member and two cams connected to the cups for providing snap release of the latch member, in either of two directions of movement of the cams, whereby, when the weight of the lower cup is in excess of the counterweight, but only then, the lower cup will drop, to actuate one cam to release the latch member, and will move the linkage to move the valve to open with a snap action, the latch member then moving to relatch the linkage, but this time in its valve-open position, and whereby, when the upper cup is raised by a rise of the liquid level, it will move the other cam to release the latch member and the linkage will move to valve closing position with a snap action, the latch member then moving to relatch the linkage, but this time in its valve-closed position, the linkage comprising a parallelogram having two vertical members, one of which is counterweighted to give the linkage a tendency to move to valve closing position, and the other one of which fixedly mounts the upper inverted cup and the lower cup, and which also mounts the two cams, the latch member being disposed near such cams.

OTTO THIEL.
